UNITED STATES PATENT OFFICE.

THOMAS F. McGANN, OF BOSTON, MASSACHUSETTS.

IMPROVEMENT IN GAS-BURNERS.

Specification forming part of Letters Patent No. **152,568**, dated June 30, 1874; application filed May 15, 1874.

To all whom it may concern:

Be it known that I, THOMAS F. McGANN, of Boston, in the county of Suffolk and State of Massachusetts, have invented certain Improvements in Gas-Burners, of which the following is a specification:

Figure 1 of the accompanying drawing is a central vertical section of my improved gas-burner. Figs. 2 and 3 are central vertical sections of modifications embodying the general principles of the same, with the outer cap removed. Fig. 4 is an interior view of a modification of a portion of the burner.

The object of the present invention is to direct and regulate the passage of, so as to economize, gas, to produce a steady flame, and prevent the whistling or disagreeable noise occasioned by the passage of gas through ordinary burners; and to effect these ends my improvements consist in a gas-burner constructed, arranged, and operating as I will now proceed to describe and point out in the claim.

In the drawing, A represents a base of a burner formed with a bottom interior screw-socket, a, to screw on a gas-pipe, and formed with a top shoulder and screw-stem, b, to receive a burner-cap, B, formed as usual, or otherwise, and provided with a lava or other tip, C. A vertical aperture extends through the center of the stem b and base A, and is formed at the top with screw-threads to receive and hold, or allow the release of, a hollow tube or vertical stem, c, perforated in its upper portion with orifices, as at d, Figs. 1 and 3, or slotted at the top sides, as at d', and formed with a circular flange or collar, d'', perforated as shown in Fig. 2, or otherwise formed, as desired, to allow the introduction of gas within the upper portion of a cap or shell, D, formed to screw, so as to be raised and lowered, on the tube or stem c, to admit the bottom of the shell or cap D being raised above or brought down upon a beveled or other seat formed on the top of the stem b, to lessen or increase the opening caused by the rising of the cap or shell between the bottom of the cap or shell and its seat, and regu-

late the flow of gas, which passes up through the central aperture of the tube or stem c, out through the orifices d, or slots d', and perforated disk or collar d'', down between the tube c and cap or shell D, and out through the opening between the bottom of the shell D and seat or top of stem b, into the outer cap B, from which it finds an exit through the tip in the form of flame. Above the cap or shell D, as represented in Fig. 1, is a check nut or cap, f, that turns on the top of the tube, c, and bears upon the top of the cap or shell D, to regulate it and hold it in position to admit the desired flow of gas; or the cap or shell D may have a solid top, as shown in Figs. 2 and 3, to form a cap for the tube c, whose central aperture may be readily freed of obstructions by removing the cap and blowing through the tube; and for this purpose, besides its other functions, the nut or cap f is preferable, for it may be readily removed to open the end of the tube c without disturbing the shell or cap D, when adjusted to admit the flow of gas desired.

The bottom of the inner periphery of the shell or cap D is beveled or otherwise formed to incline the passage between it and the beveled or other formed seat of the base, and may, if desired, be notched out on the bottom, as shown in Fig. 4, or otherwise constructed to form a passage or passages for the escape of gas between it and its seat.

By the above description, reference being had to the drawings, it will be readily seen, without further explanation, that the gas passing up the tube c, through its orifices d, and then down between it and the shell D, enters, through the passage between the shell and seat, the outer cap with less impetuosity than when admitted therein as ordinarily, thus producing an even flow of gas without the disagreeable noise ordinarily produced by the direct and sudden influx of gas into the burner. It will be also seen that the flow of gas is readily regulated as desired by raising or lowering the cap or shell D by turning it on the stem or tube c, and enlarging or diminishing the passage between the bottom of the cap or

shell and the seat, thus using the amount of gas required to produce the desired flame and preventing the waste of gas usual in ordinary burners.

Having thus described my improvements, what I claim as my invention, and desire to have secured to me by Letters Patent, is—

In a gas-burner the combination of the perforated screw-stem or tube *e*, base *A*, cap or shell *D*, cap-nut *f*, and burner-cap *B*, all ar-

ranged and operating substantially as and for the purpose set forth.

In testimony whereof I have signed my name to this specification in the presence of two subscribing witnesses.

THOMAS F. McGANN.
